United States Patent Office

Des. 203,840
Patented Feb. 22, 1966

203,840

TOY SODA FOUNTAIN

Karl A. Utrecht, Cincinnati, Ohio, assignor to Kenner
Products Company, Cincinnati, Ohio, a corporation of Delaware

Filed May 5, 1965, Ser. No. 85,111

Term of patent 3½ years

(Cl. D34—15)

H. Utrecht

Fig. 2

Fig. 5

Fig. 6

FIG. 4

I claim:

The ornamental design for a toy soda fountain, substantially as shown.
